UNITED STATES PATENT OFFICE.

AUSTIN F. JACKSON, OF TAUNTON, MASSACHUSETTS.

DESIGN FOR A HANDLE FOR SPOONS, &c.

SPECIFICATION forming part of Design No. 25,692, dated June 30, 1896.

Application filed May 26, 1896. Serial No. 593,184. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles for Spoons, Forks, &c., of which the following is a specification, reference being had to the accompanying drawings, showing a part thereof.

My invention is in the nature of a new design for the handles of spoons, forks, knives, and like articles.

Figure 1 is a front face view of such handles as applied to a spoon, and Fig. 2 is a back view.

The general contour is a wide end *a*, curving inwardly and then swelling outwardly again at *b*, and then drawing inwardly again to form the shank of the handle.

The principal features of the front face of the design is a smooth convex panel *a'*, a terminal ball *a³*, with symmetrical marginal scrolls *a⁵* on each side, and inturned scrolls *a²*. Beaded scrolls *a⁴* extend along down toward

the swelled portion *b*, which latter has marginal inturned scrolls *b'*. A marginal bead *b²* extends along the shank portion to the swelled portion of the spoon-bowl or fork-head, and terminates in a scroll *b³*, displayed along the edge of the latter.

The principal features of the back side of the handle is a concave panel *a⁷*, whose end is surmounted with the same terminal ball *a³* and symmetrical scrolls *a⁵* that appear on the face. A marginal head *a⁶* extends along the edge of the wide portion of the handle to the swelled middle part, which latter has a series of inturned shoots or buds *b⁴*. The same marginal head *b²* which appears on the front side also appears on the back side of the shank, while a shell pattern of scrolls *c* is placed on the broad end of the bowl of the spoon or broad head of the fork at the point where the handle joins onto it.

What I claim is—

45

1. The design for the front face of the handles of spoons, forks, &c., substantially as herein shown and described.

2. The design for the back face of the handles of spoons, forks, &c., substantially as herein shown and described.

3. The design for the handles of spoons, forks, &c., substantially as herein shown and described.

AUSTIN F. JACKSON.
